(57) **ABSTRACT**

A new and distinct cultivar of Poinsettia plant named 'Eckacar', characterized by its smooth creamy white bracts; response time about 8.5 weeks; very dark green leaves; upright and freely branching plant habit; and excellent postproduction longevity.

2 Drawing Sheets

1

BACKGROUND OF THE INVENTION

The present invention relates to a new and distinct cultivar of Poinsettia plant, botanically known as *Euphorbia pulcherrima* Willd., and hereinafter referred to by the name 'Eckacar'.

The new cultivar is a product of a planned breeding program conducted by the Inventor in Encinitas, Calif. The objective of the program is to create new Poinsettia cultivars having interesting bract and leaf display, color and form; strong and freely branching stems; and good postproduction longevity.

The new cultivar originated from a cross made by the Inventor of the proprietary Poinsettia selection identified as 564, as the female, or seed parent, with the Poinsettia 10 cultivar 'PJ 3112', disclosed in U.S. Plant Pat. No. 9,066, as the male, or pollen parent.

20 The cultivar 'Eckacar' was discovered and selected by the Inventor as a flowering plant within the progeny of the stated cross in a controlled environment in Encinitas, Calif. in December, 1996.

25 Asexual reproduction of the new Poinsettia by terminal cuttings taken at Encinitas, Calif., has shown that the unique features of this new Poinsettia are stable and reproduced true to type in successive generations of asexual reproduction.

BRIEF SUMMARY OF THE INVENTION

30 The following traits have been repeatedly observed and are determined to be the unique characteristics of 'Eckacar'. These characteristics in combination distinguish 'Eckacar' as a new and distinct cultivar:

1. Smooth creamy white bracts.
2. Response time about 8.5 weeks.
3. Very dark green leaves.
4. Upright plant habit.
5. Freely branching habit.
6. Excellent postproduction longevity.

In side-by-side comparisons conducted in Encinitas, Calif., plants of the new Poinsettia are taller and have smaller and brighter white bracts than plants of the female parent, the selection 564. Plants of the male parent, the

2

cultivar 'PJ 3112', have red-colored bracts whereas plants of the new Poinsettia have creamy white bracts.

Plants of the new Poinsettia can be compared to plants of the cultivar '490 White', disclosed in U.S. Plant Pat. No. 8,772. However, in side-by-side comparisons conducted in Encinitas, Calif., plants of the new Poinsettia differed from plants of '490 White' in the following characteristics:

1. Plants of the new Poinsettia are taller and more upright than plants of '490 White'.
2. Plants of the new Poinsettia have wider leaves and longer petioles than plants of '490 White'.
3. Plants of the new Poinsettia have smaller, smoother, flatter and more white-colored bracts than plants of '490 White'.
4. Plants of the new Poinsettia flower later than plants of '490 White'.

BRIEF DESCRIPTION OF THE PHOTOGRAPHS

The accompanying colored photographs illustrate the overall appearance of the new Poinsettia, showing the colors as true as it is reasonably possible to obtain in colored reproductions of this type.

25 The photograph at the top of the first sheet comprises a side perspective view of a typical plant of 'Eckacar'.

The photograph at the bottom of the first sheet comprises a top perspective view of a typical plant of 'Eckacar'.

30 The photograph on the second sheet is a close-up view of typical bracts and leaves of 'Eckacar' (left) and '490 White' (right). Bract and foliage colors in the photographs may differ from actual colors due to light reflectance.

DETAILED BOTANICAL DESCRIPTION

35 The new Poinsettia has not been observed under all possible environmental conditions. The phenotype may vary somewhat with variations in environment such as temperature, daylength and light intensity, without, however, any variance in genotype. The following observations and measurements are averages that describe plants grown in Encinitas, Calif., under commercial practice in a glass-covered greenhouse with day temperatures ranging from 21 to 27° C., night temperatures ranging from 18 to 20° C., and light levels about 4,000 foot-candles. Plants were

grown in 16-cm pots, pinched one time, and flowered under naturally lengthening nights during the fall/early winter.

In the following description, color references are made to The Royal Horticultural Society Colour Chart except where general terms of ordinary dictionary significance are used.

Botanical classification: *Euphorbia pulcherrima* Willd. 'Eckacar'.

Parentage:

Female parent.—Proprietary selection of *Euphorbia pulcherrima* Willd. identified as 564.

Male parent.—*Euphorbia pulcherrima* Willd. 'PJ 3112', disclosed in U.S. Plant Pat. No. 9,066.

Propagation:

Type cutting.—Terminal cuttings.

Time to initiate roots.—Summer: About 7 days at 24° C. Winter: About 10 days at 22° C.

Time to develop roots.—Summer: About 26 days at 24° C. Winter: About 26 days at 22° C.

Rooting habits.—Freely branching, becoming fibrous with development.

Plant description:

Plant form.—Inverted triangle.

Growth habit.—Upright. Freely branching. Branching is enhanced by removing the shoot apex.

Plant vigor.—Moderate.

Plant height.—About 29 cm.

Crop time.—From unrooted cuttings to a flowering plant in a 16-cm container, about 16 weeks are required.

Stem description.—Thick, strong stems. Number of lateral branches: About five lateral branches are formed after removal of the terminal apex. Lateral branch length: About 22.5 cm. Internode length: About 2.25 cm. Stem color: 146A.

Foliage description.—Quantity of leaves per lateral branch: About 7. Length: About 11.5 cm. Width: About 9 cm. Shape: Ovate to lobed. Apex: Acuminate. Base: Rounded acute. Margin: Entire. Texture: Smooth, matte; very sparse pubescence on lower surface. Color: Young foliage, upper surface: Darker than 137A. Young foliage, lower surface: 137C. Mature foliage, upper surface: Very dark green, darker than 139A. Mature foliage, lower surface: 137A. Venation, upper surface: 144C. Venation,

lower surface: 138C. Petiole: Length: About 4.9 cm. Diameter: About 3 mm. Color: 144B.

Inflorescence description:

Inflorescence type and habit.—Inflorescences are compound corymbs of cyathia with colored flower bracts subtending the cyathia.

Natural flowering season.—Autumn/winter in Northern Hemisphere. Flower initiation and development can be induced under long night conditions. Response time is about 8.5 weeks.

Quantity of inflorescences.—One per lateral branch, usually about five per plant.

Inflorescence size including bracts.—Diameter: About 29.5 cm. Height (depth): About 2.75 cm.

Flower bracts.—Quantity of flower bracts per inflorescence: Usually about 16 primary bracts and about 6 smaller secondary bracts per inflorescence. Length, largest bracts: About 12 cm. Width, largest bracts: About 7.75 cm. Shape: Ovate, occasionally lobed. Apex: Acuminate. Base: Acute. Margin: Entire. Texture: Smooth. Aspect: Held mostly horizontal. Color: Developing, upper surface: 11C. Developing, lower surface: 11C. Mature, upper surface: 10D. Mature, lower surface: 11D.

Cyathia.—Quantity: Usually about 13 per corymb. Diameter of cyathia cluster: About 2 by 2.5 cm. Length: About 1 cm. Width: About 5 mm. Color: Immature: 144A. Mature: 144B. Peduncle: Length: About 3 mm. Aspect: Strong, erect. Color: 145A. Stamens: Stamen number: Five to ten true stamens with numerous stamnodes per cyathium. Anther length: About 1 mm. Anther shape: Oval. Anther color: 13B. Amount of pollen: Scarce. Pollen color: 7A. Pistils: No pistillate flowers observed. Nectary color: 14A to 14B.

Disease resistance: Plants of the new Poinsettia have not been observed to be resistant to pathogens common to Poinsettias.

Postproduction longevity: Excellent; generally plants maintain good substance and bract color for about eight weeks under interior conditions.

It is claimed:

1. A new and distinct cultivar of Poinsettia plant named 'Eckacar', as illustrated and described.
